UNITED STATES PATENT OFFICE.

KIRBY D. MACLEAN, OF PALO ALTO, CALIFORNIA.

CONCRETE SOCKET-PILE.

1,074,275.

Specification of Letters Patent.

Patented Sept. 30, 1913.

Application filed November 20, 1912. Serial No. 732,591.

To all whom it may concern:

Be it known that I, KIRBY DONALD MACLEAN, a citizen of the United States, residing at Palo Alto, in the county of Santa Clara and State of California, have invented a new and useful Concrete Socket-Pile; and I do hereby declare the following to be a full, clear, and exact description of the same, reference being had to the accompanying drawings, forming part of this specification, and to the figures and letters of reference marked thereon.

The object of the present invention is to provide a pile for use in marine structural foundation work which will be protected from decay, the attacks of marine insects and various aqueous animal life, and at the same time a pile which will be of relatively small cost and adapted for being handled and driven in accordance with well understood practice with machinery now in common use.

With these objects in view, the pile of the present invention embodies a monolithic reinforced concrete body portion, solid in cross section and at its lower end having an internal elongated socket in which is fitted the upper end of a timber pile or extension, which timber pile or extension, by reason of its connection with the reinforced concrete body, will be held in alinement with said body and the whole structure may be driven by power applied to the upper end of the pile, as a unit, after the manner of driving ordinary piles by machinery now in common use.

In the preferred construction the main portion of the body of the reinforced concrete pile is of less cross sectional area than the socket portion, whereby the volume of material used in its construction is materially reduced and at the same time the average strength of the pile throughout its length is maintained and the pile is rendered competent to withstand lateral strains, even though it is apparently of small cross sectional area.

In practice, an ordinary timber pile is first driven into the mud, a suitable distance, and its upper end shaped to fit within the elongated socket of the enlarged lower end of the concrete pile. The concrete socket pile is then placed in position on the upper end of the timber pile and in alinement therewith, and the two sections allowed to seat one within the other, whereby the aline-

ment is preserved, after which the whole structure is driven as a unit by blows applied to the upper end of the concrete pile. The penetration which should be secured is 60 such that the timber extension and the socket are both below the mud line, leaving only the concrete portion of the structure in position where attack from marine animal life or low forms of vegetable growth, such as 65 result in the decay of timber fiber, will be likely to take place. The timber portion of the pile is thereby entirely removed from destructive influence and the pile as a whole will be practically indestructible, inasmuch 70 as the reinforced concrete pile is not influenced by the conditions to which it is subjected.

Referring to the accompanying drawings, Figure 1 is an isometric projection of a 75 concrete socket pile embodying the present invention. Fig. 2 is a vertical section of the concrete socket pile and its timber extension showing the method of their assemblage and use. Fig. 3 is a transverse section 80 through the shaft of the concrete pile in a plane indicated by the lines *c-c*, this view showing one method of reinforcing. Fig. 4 is a transverse section through the socket portion of the pile in a plane indicated by the line *B-B*, this view also showing the reinforcement material embodied in the concrete. 85

Like letters of reference in the several figures indicate the corresponding parts. 90

It will be understood that the concrete pile is adapted to be cast in suitable molds or otherwise and allowed to set before it is positioned for driving, and it therefore is of the type which may be properly designated as a "pre-cast or formed pile" as contradistinguished from reinforced concrete piles which are cast *in situ*, and which are not adapted for subsequent driving in the formation of a solid foundation. 100

In said drawings the shaft or main body portion of the pile is as shown in the section in the plane *c-c*, Fig. 3, of relatively small transverse area, the size, of course, being determined by the strains to which it will be 105 subjected by the super-structure adapted to be supported by it. The reinforcing material *c* is also distributed and arranged in the shaft in accordance with known principles for affording the desired strength, although said reinforcement is also preferably in the main formed by longitudinal re-

inforcing members which extend more or less continuously from one end to the other of the pile and are connected together by lateral reinforcing metal which may be 5 wound about them during or prior to the mold being filled with the plastic concrete composition. At the lower end the shaft is transversely enlarged and formed with an internal socket α , β which is preferably of 10 cylindrical form, and additional reinforcing metal e is extended around the socket in the body of concrete to resist lateral strains, as shown clearly in Fig. 4.

In Figs. 3 and 4 the main reinforcing metal is indicated by the reference letters c and d , but it will be understood that while the arrangement shown is preferred, I do not wish to be limited thereto, save in so far as specifically designated in the claims, inasmuch as other effective arrangements of the reinforcing metal may be employed and still secure passably good results, particularly if the longitudinal reaches of the reinforcing metal extend from end to end of the 25 pile, so as to effectively resist lateral strains tending to break or bend the pile at any point in its length and also to serve as a means for effectively transmitting the driving blows to all parts of the mass constituting the pile.

In making use of a pile embodying the present improvement, it is preferred that the wooden or timber extension shown in Fig. 2 be first driven at the desired point until its upper end is substantially at the water line and then the concrete pile is fitted on the same with the upper end of the timber extension seated firmly in the socket, whereupon the driving operation is continued in 40 the ordinary way until the upper end of the timber extension and the socket enlargement of the concrete pile are well below the mud line of the bottom. The long socket serves to hold the concrete pile and its extension in alinement during the driving operation and furthermore is of sufficient strength to resist lateral pressure on the upper end of the shaft or body of the concrete pile and transmit any such pressure to the 45 timber extension. The body or shaft of the concrete pile and the timber extension are in direct alinement with each other so that the pressure of the driving blows is transmitted directly from one to the other and does 50 not produce lateral strains in the concrete mass, such as would tend to disrupt or shear the same during the driving operation.

The position of the pile when driven is indicated in Fig. 2, where m , n represent the

water line and h , g the mud line on a pile 60 which has been driven to its final seat.

With the construction of concrete pile described the quantity of material necessary to be employed may be very considerably reduced as compared with concrete piles heretofore constructed, for not only may the timber extension which is very much cheaper than the concrete, be employed without detracting from the strength or efficiency of the structure, but the cross sectional area of 70 the body of the concrete pile or shaft portion may be made much less than is necessary where tubular piles are employed as has heretofore been suggested.

Having thus described my invention, what 75 I claim as new and desire to secure by Letters Patent of the United States, is:

1. A monolithic reinforced concrete pile embodying a shaft or body portion solid in cross section and having its lower end enlarged in cross section and formed with an internal elongated socket having its axis in line with the axis of the solid shaft or body portion, said socket being adapted to form an elongated chamber in which the upper 80 end of a timber extension will seat and be held in alinement with the solid shaft or body portion, whereby the concrete pile and its timber extension may be driven as a unit by power applied to the upper end of the 85 shaft or body portion.

2. A pre-cast, monolithic concrete pile embodying a shaft, solid in cross section and having its lower end enlarged and formed with an elongated internal socket having its 90 axis in line with the axis of the solid shaft, said shaft and the walls of said socket having incorporated therein longitudinally extending reinforcing metal and transversely arranged reinforcing metal, said socket forming 100 an elongated chamber, and a timber extension having its upper end fitting and seating in said chamber, whereby said timber extension will be held in alinement with the solid shaft and the whole structure may be driven as a 105 unit by power applied to the upper end of the shaft without causing shearing strains tending to disrupt the concrete portion of the structure.

In testimony whereof, I have signed my 110 name to this specification in the presence of two witnesses, this 14th day of November, A. D. 1912.

K. D. MACLEAN.
